UNITED STATES PATENT OFFICE

EDGAR D. TILLYER, OF SOUTHERBRIDGE, MASSACHUSETTS, ASSIGNOR TO AMERICAN OPTICAL COMPANY, OF SOUTHERBRIDGE, MASSACHUSETTS, A VOLUNTARY ASSOCIATION OF MASSACHUSETTS

CRYSTAL OSCILLATOR

Original application filed July 16, 1924, Serial No. 726,289. Divided and this application filed July 9, 1930. Serial No. 466,738.

The present invention relates on an improved form of crystal oscillator and has particular reference to the production of a constant frequency electric oscillator.

- 5 An important object of the invention is to provide an electric oscillating circuit of constant frequency using a crystal grid control, or piezo electric properties of certain crystals.
- 10 A further object of the invention is to provide means whereby such a crystal will be free to oscillate freely without the presence of restraining friction.

A still further object of the invention is 15 to provide means whereby high powers may be drawn from the crystal without danger of fracturing or in otherwise ruining the crystal.

Other objects and advantages of the invention will become apparent during the 20 course of the following description:

In the drawings, wherein like numerals are employed to designate like parts throughout the same,

Figure 1 is a diagrammatic view of a well 25 known type of crystal and mounting therefor.

Figure 2 is a sectional view showing one form of my invention, and

Figure 3 is an elevation showing another 30 form of my invention.

It is a well known fact that certain crystals, such as quartz, Rochelle salts and tourmaline have the peculiar property of becoming changed electrically when they are 35 compressed or stretched in certain directions. On the other hand they change their shape slightly when they are placed in an electrical field. Such crystals when vibrated mechanically will produce an alternating voltage, 40 and naturally, if they are placed in an alternating electric field they will vibrate. Such crystals are said to be possessed of piezoelectric properties.

If a piece of quartz is cut from a crystal 45 parallel to its axis and is properly mounted in an electric circuit as shown in the drawings, it may vibrate and cause the circuit to become an electric oscillator and thus a source of oscillations. If it does vibrate, the 50 vibrations are dependent upon the form of

the crystal, and its composition, and is little influenced by external sources, as is well known.

However, even if the crystal does vibrate well, when sufficient energy is applied to really produce satisfactory oscillation for power control purposes a corona appears, whereby the crystal is locally stressed beyond its limit by the additional corona and the crystal breaks down.

In the drawings, wherein for the purposes of illustration is shown the preferred embodiment of my invention the numeral 10 designates a crystal having piezo electric properties. The crystal is shown as being 55 supported between two metallic plates 11, either in contact, touching very lightly, or just clearing the metal. Wire connections 12 are associated with the plates 11, the said plates usually being brass.

There are two big difficulties encountered 60 where using the crystal as a grid control in the prior structures, namely, first, the surface of the crystal is in contact with a viscous medium under pressure, and, second, this medium permits a brush discharge to the crystal, producing local strains and heating, thus causing the fracture of a valuable crystal as soon as any appreciable power is being drawn 65 from the circuit.

The crystal normally has two directions of 70 vibration, one in the direction A to B and the other in the direction B to C (Fig. 1). This vibration travels with the velocity of sound within the crystal, which velocity is 75 much greater than sound in the air. In other words, we have a tremendous friction in the viscous medium air in trying to impart this vibration to the air surrounding the crystal. This energy is all lost and in fact 80 more than lost as the dampening may be sufficient to prevent the crystal from vibrating at all.

Many attempts have been made to overcome or to reduce the friction, such as for 85 instance, curving the face B C of the crystal but while this curved face has assisted, it has not eliminated the air viscosity.

Another great difficulty with the prior 90 structures is that with high power use a 100

corona discharge occurs. This resembles silent discharge, but it is not silent and produces local heating and energy loss, but more than this, it produces a breakdown in the 5 crystal like the presence of air in a mica condenser used for high frequency oscillations, inevitably producing a breakdown under high power. With the crystal we cannot impregnate it with wax as in the condenser 10 because the wax stops the vibration. Furthermore, we cannot add compressed air as is done in some high power air condensers, because the friction of ordinary air is undesirable and the greater the pressure the 15 greater the friction.

In accordance with my invention I remove the air friction by lowering the air pressure. A moderate reduction in pressure will accomplish this to a limited extent, but will 20 increase the corona discharge. However, if the air pressure is still further lowered the corona discharge will no longer pass between the plates and the crystal even if present. A still further reduction in the air pressure will 25 stop all discharge and eliminate the air friction. Probably the best point of operation is where the discharge is stopped for the voltage used.

In Figures 2 and 3 is shown a crystal oscillator so arranged that it can readily be 30 used as a grid oscillator control. The crystal 10 and plates 11 are mounted in bulb 13 in which is formed either a complete or a partial vacuum. In Figure 3 the bulb is provided 35 with a base 14 so that the bulb can easily be placed in or removed from a circuit easily and rapidly. By mounting the crystal and holder in a vacuum the corona cannot be present. Furthermore, the crystal is more 40 stable, will stand much higher voltage and will vibrate much more freely because of the absence of air viscosity.

This application is a division of my prior 45 application Serial Number 726,289, filed July 16, 1924 entitled "Crystal oscillator".

It is to be understood that the form of the invention herewith shown and described is to be taken as the preferred embodiment of the same and that various changes may be made 50 in the shape, size and arrangement of parts without departing from the spirit of the invention or the scope of the subjoined claims.

I claim:

1. A piezo-electric crystal holder comprising in combination a hermetically sealed bulb 55 and means within said bulb for securing a piezo-electric crystal therein and establishing electrical connection therewith to said crystal through said bulb, while permitting the free vibration of said piezo-electric crystal with substantially no restriction, the space 60 within said bulb being evacuated.

2. A piezo-electric oscillator having in 65 combination a hermetically sealed bulb, a piezo-electric crystal therein, means within

said bulb for mounting said crystal and establishing electrical connection therewith, electrical connections extending through said bulb to said mounting, the space within said bulb being evacuated.

70

3. A piezo-electric crystal holder comprising in combination a base plug, an evacuated bulb secured to said plug, means for supporting a piezo-electric crystal within said evacuated bulb, and means for establishing electrical connection with the said crystal from points on said plug which are exterior to said bulb.

75

4. A piezo-electric crystal holder comprising in combination a screw base plug, a glass evacuated housing secured to said plug, means for supporting a piezo-electric crystal within said housing, and means for establishing electrical connection with said crystal from points on said plug which are exterior 80 to said housing.

85

5. A piezo-electric crystal holder comprising a base plug having a stem, a housing enclosing the stem and supported by the plug, electric connections through the stem, a pair 90 of separated plates one each being carried by one of said electric connections, and a piezo-electric crystal held between the plates.

95

6. A piezo-electric crystal holder comprising a closure, a pair of wires extending into the closure, a plate supported by each wire, and a piezo-electric crystal held between the plates.

100

7. A piezo-electric crystal holder comprising in combination an evacuated and sealed closure, a pair of wires extending through and into the closure, a plate carried by each wire, and a piezo-electric crystal supported 105 between the plates.

105

8. A piezo-electric oscillator including a hermetically sealed bulb, electrodes within said bulb, a piezo-electric crystal interposed between said electrodes, means within said bulb for holding said electrodes in spaced relation, and terminals on the exterior of said bulb which are in electrical communication respectively to said electrodes through the bulb.

110

In testimony whereof I have signed my 115 name to this specification.

EDGAR D. TILLYER.
